US00D905076S

(12) **United States Design Patent** (10) **Patent No.:** **US D905,076 S**
James (45) **Date of Patent:** **** Dec. 15, 2020**

(54) **COMPUTING DEVICE DISPLAY SCREEN WITH GRAPHICAL USER INTERFACE FOR SPILL RISK ASSESSMENT SUMMARY**

(71) Applicant: **NEW PIG CORPORATION**, Tipton, PA (US)

(72) Inventor: **Andrew Ian James**, Warriors Mark, PA (US)

(73) Assignee: **New Pig Corporation**, Tipton, PA (US)

(**) Term: **15 Years**

(21) Appl. No.: **29/637,439**

(22) Filed: **Feb. 19, 2018**

Related U.S. Application Data

(63) Continuation of application No. PCT/US2017/058437, filed on Oct. 26, 2017, and a continuation of application No. 15/794,323, filed on Oct. 26, 2017.

(57) **CLAIM**

The ornamental design for a computing device display screen with graphical user interface for spill risk assessment summary, as shown and described.

DESCRIPTION

The FIGURE is a front view of a computing device display screen with graphical user interface for spill risk assessment summary.

The outermost broken line rectangle shows a display screen and forms no part of the claimed design. All other broken lines show portions of the graphical user interface and form no part of the claimed design.

1 Claim, 1 Drawing Sheet

New Construction Pad

Drum/IBC Storage Area

Oils or oil-based Spills, Comastics, Others						
46 ft	1	3	High			
Liquid area to drain distance	Obstruction factor	# of liquid types	Visibility of potential spills			
275 gal	90 ft	287 ft	Yes			
Largest container	Spill Reach (ft)	Spill Reach (ft)	Com/Fammables			
(largest container vol. of water, on flat surface)	(largest container vol. of water, on 5° slope)					
Very High		High	High			
Area Drain Risk		Area Liquid Risk	Response Pressure			
The risk that your largest container spill could reach the nearest drain. The risk of responders confusing liquid types during response, with emphasis placed on hazardous liquids						
types during response, with emphasis placed on distance to drain, type and number of liquids, and visibility						

Drain Sealing Equip.	141 ft x 12 = 133 ft ²		
	Blocker to drain distance	Obstruction factor	Effective distance to drain
141 ft x 1.1 = 133 ft ²			
Not Acceptable	Borderline	Good	
Blocker Distance	Blocker Visibility	Drain Condition	
Consider spill reach, level of obstruction between drain and blocker, and Response Pressure	Consider points of visibility from drain, level of visibility, and Response Pressure	Important for drain blockers or plugs to be seal tightly	

160 ft x 1.1 = 176 ft = 300 gal ²			
Liquid area to spill kit	Obstruction factor	Effective distance to kit	Estimate kit absorbency
160 ft x 1.1 = 176 ft			
Not Acceptable	Not Acceptable	Not Acceptable	
Spill Kit Capacity	Spill Kit Distance	Spill Kit Visibility	
Based on ratio of largest container to kit absorbency and distance to drain	Considers spill reach, level of obstruction between area and kit, Response Pressure, and kit mobility	Consider points of visibility from liquid area, level of visibility and Response Pressure
